THE FIRM VOIGT & HAEFFNER AKTIENGESELLSCHAFT, OF FRANKFORT-ON-THE-
MAIN, GERMANY

MANUFACTURE OF ELECTRIC HEATING BODIES

Application filed September 1, 1928, Serial No. 303,479, and in Germany September 5, 1927.

The present invention has reference to the manufacture of electric heating bodies, in particular heating plates, in which the heat conductor is disposed inside an insulating mass. In the manufacture of such heating bodies, and especially in the bedding-in of the heat resistances, particularly when same are of spiral or similar shape, certain difficulties occur in inserting these spirals either at precisely uniform distances from each other or, when metallic radiation plates are used, to ensure the distance of the spirals from the said plates, or from the grooves connected with these plates, being perfectly uniform.

These difficulties are avoided by the process forming the object of this invention, according to which the said heat conductor, for example a heating spiral, is first pressed lightly into a loosely heaped insulating material, and further insulating material is then inserted, whereupon the final bedding-in of the heating material is either finished direct under pressure or with the insertion of the said radiation plates. The process here is as follows: On the base plate of a suitable press tool, which is surrounded by a removable ring, insulating material is first filled in. Then by means of a special tool, the heating element, which is constructed in the form of a heating spiral or in other suitable form, is pressed in on the surface. Then this tool is removed, the space filled with further insulating material and, in the case of heating bodies without heating plate, the pressure is completed by means of a flat plate under suitable pressure, or the radiation plate is set in position, and both the heating material and its insulating mass is suitably connected under pressure with the radiation plate. At the end of this pressing operation, the insulating material is secured i. e. the conversion of the insulating material into a fixed form, as nearly as possible unalterable, is effected by heating the heating element either directly or indirectly through current.

In the drawings a suitable device for carrying out the present process is represented by way of example.

Figures 1 to 5 inclusive illustrate sectional views of an apparatus for carrying out the

present process, the various steps of the method being successively indicated in said figures; and Figure 6 is a plan view of a tool employed for holding the heat conductor during the process of imbedding the same in the insulating material.

In said drawings, *a* is the actual pressure block, *b* is a ring surrounding the same which can be pressed downwards against the tension of the springs *c*. *d* and *e* are apertures for the introduction of the connecting wires of the heating spiral and *f* is the loosely heaped insulating mass.

Figure 1 shows the separate parts of the pressing device at the moment before the pressing in of the spiral *g*. This operation takes place by means of a tool *h* represented in Figure 6, which may, for example, be provided with two spiral-shaped cut-out portions in which the heating spirals *g* are inserted. On the tool *h* there rests, further, another tool ring *i*. Pressure is exerted on parts *h* and *i* by a spring *k*. Now, when downward pressure is applied to the plunger *l* fitted in the pressure block *a*, the tool *h* presses the heating spiral *g* into the loose insulating material *f*, (Figure 2). At the same time, pressure is transmitted to the tool ring *i* under the effect of the spring *k*, so that the tool *h* simultaneously exerts a downward pressure. In this way the insulating material underneath the members of the tool *h* containing full material is slightly compressed, and thus any possibility of the heating spiral *g* being displaced in a lateral direction on the pressing-in of the insulating material is avoided, i. e. the heating spiral *g* is pressed into the mass *f* at the precise distance which it is given in the tool *h* by the spiral-shaped cut-out portions. Figure 2 shows the parts of the pressing device at the moment when the first slight pressing-in of the heating spiral *g* is concluded. Then the pressing tools *h* and *i* are removed and the space above the spiral *g* is filled with insulating material. Should a heating element without metallic radiation plate be made, a flat plate *m* is set in position and the body compressed (Figure 3) under a correspondingly high pressure. If, on the other hand, the

heating material is pressed into a radiation plate *n*, then, as shown in Figure 4, the plate *n*, which can be provided with wedge shaped rings and suitably introduced in a lateral direction, is pressed into the material *f* under a very high pressure. In this case the plate *n* with its rings presses into the insulating material, while the ring *b* is compressed. The plate *n* then forms, with the heating spiral *g* of the insulating material *f*, a comparatively rigid body, as shown in Figure 5.

In order not to damage the connecting wires of the spirals *g*, these are pushed through the apertures *d* and *e* on being introduced into the tool ring *h*. The construction of the individual tool rings can vary considerably to correspond with the construction of the heating body. The only essential feature is that the heating spiral *g* in its insulating material *f* should first be lightly pressed by the heating body, then filled up again with insulating material, and finally the required rigid heating body is brought into suitable form under pressure.

In the manufacture of heating plates, according to the process hereinbefore described, a comparatively porous and irregular surface is obtained in general. Further, the insulating material used possesses hygroscopic properties which are prejudicial to the lasting uniformity of the heat resistances. To avoid this defect, according to this invention for the lowest layer i. e. in heating plates or cast bodies, for the last heaped material, a layer is used which consists essentially of ceramic material with necessarily low electric insulating properties, but which provides a smooth outside layer capable of resisting detrimental effects and at the same time shuts off the actual insulating mass from hygroscopic phenomena by virtue of its own material. As material for this purpose ceramic masses such as steatite, porcelain or the like can be used.

What I claim is:

The process of manufacturing electrical heating bodies, which comprises suitably confining a layer of dry powdered insulating material of uniform density throughout the depth thereof, then imbedding an electrical conductive heating body in said dry layer by applying a slight pressure to said body and simultaneously slightly compressing said dry layer for the purpose of preventing said body from being displaced within said layer, laying a second layer of the same insulating material over the first-mentioned layer, then applying a layer of ceramic material to the second-mentioned layer, applying a heavy pressure to said layers to form said layers into a solid mass and heating said conductor.

In testimony whereof I affix my signature.
